UNITED STATES PATENT OFFICE.

HORACE J. MIER AND DAVID BEAMES, OF RUTHERFORD, NEW JERSEY.

HEN'S NEST AND HATCHING-COOP.

No. 841,995.

Specification of Letters Patent.

Patented Jan. 22, 1907.

Application filed June 28, 1906. Serial No. 323,853.

To all whom it may concern:

Be it known that we, HORACE J. MIER, a citizen of the United States, and DAVID BEAMES, a subject of the King of Great Britain, residing at Rutherford, in the county of Bergen and State of New Jersey, have invented certain new and useful Improvements in Hens' Nests and Hatching-Coops, of which the following is a specification, such as will 5 enable those skilled in the art to which it appertains to make and use the same.

This invention relates to hens' nests and hatching-coops; and the object thereof is to provide an improved device of this class having improved means of ventilation and which may be placed on the ground or on an elevated support of any kind or class and which may be used in a hen-house or independent of or outside of such structure.

20 The invention is fully disclosed in the following specification, of which the accompanying drawings form a part, in which the separate parts of our improvement are designated by suitable reference characters in 25 each of the views, and in which—

Figure 1 is a side view of our improved hen's nest and hatching-coop; Fig. 2, a section on the line 2 2 of Fig. 1, and Fig. 3 a plan view.

30 Our improved hen's nest and hatching-coop comprises a box-shaped base portion *a* and a roof portion *b*. The box-shaped base portion *a* is provided with an open-work bottom *a*², composed in the form of construction 35 shown of wire-mesh, but which may be composed of any desired open-work material. The roof portion *b* comprises an open framework having an angular base *b*², similar in form to the top of the box-shaped base portion *a* and preferably provided with two inclined sides *b*³, having a waterproof covering *b*⁴ of any suitable material, and the roof portion *b* is also provided with a horizontal top member *b*⁵, with which is connected a handle *b*⁶, by means of which the device may be conveniently moved from one point to another.

40 The opposite gable end portions *b* are composed of open-work members *b*⁷, preferably consisting of interwoven wire or similar material, said open-work members being hinged to the base-frame *b*² of the roof portion, as shown at *b*⁸, so that they may be let down, as shown at the left of Fig. 2, or raised and locked in position, as shown at the right of 45 said figure, and for this purpose said open-work members *b*⁷ are provided with hooks *c*

at the top thereof, adapted to engage catches, pins, or loop members *d*, secured to the top of the roof portion *b*. The roof portion *b* is detachably connected with the base member *a* by means of hooks or similar fastening devices, as shown at *e*, in the form of construction shewn, and in practice the base portion *a* of the device is filled or partially filled with straw or other suitable material. 65

When the device is in use as an ordinary hen's nest in which the hens may lay their eggs, the parts *b*⁷ may both be lowered, as shown at the left of Fig. 2, and when desired—as, for instance, when a hen is setting—either 70 or both of said parts *b*⁷ may be raised and locked in position, as shown at the right of Fig. 2, and said parts *b*⁷, or one of them, may be lowered at any time, as shown at the left of Fig. 2, in order to allow the hen to temporarily leave her nest. 75

By providing the open-work bottom *b*² for the base portion of the device the nest itself is thoroughly ventilated, and the said device may be placed on dry ground, and this is 80 sometimes an advantage in devices of this class, or, if desired, the said device may be placed on an elevated support in such manner that the air will be free to circulate under and through the nest, and by providing open-work gable end members which may be locked in a closed position we also provide 85 means for protecting the hen at night from prowling animals, and said open-work members when locked in the closed position also prevent interference with a setting hen by other fowls or other animals in the day-time.

Our improved hen's nest and hatching-coop may be made of any desired material and of any preferred form. 95

Having fully described our invention, what we claim as new, and desire to secure by Letters Patent, is—

1. A hen's nest and hatching-coop, comprising a box-shaped base portion having an open-work bottom and a roof portion provided with open-work gable end members which are hinged to the base of the roof portion. 100

2. A hen's nest and hatching-coop, comprising a box-shaped base portion having an open-work bottom and a roof portion provided with open-work gable end members which are hinged to the base of the roof portion, said roof portion being detachably connected with the base portion. 105

3. A hen's nest and hatching-coop, com-

prising a box-shaped base portion having an open-work bottom and a roof portion provided with open-work gable end members which are hinged to the base of the roof portion, said roof portion being detachably connected with the base portion, and the roof portion being provided at the top with a handle.

4. A hen's nest and hatching-coop, comprising a box-shaped portion having a roof-shaped top portion, said top portion being composed of a frame having inclined waterproof side and open-work gable ends, said gable ends being hinged at the base of the top portion and provided with means for locking them in the closed position.

5. A hen's nest and hatching-coop, comprising a box-shaped base portion and a top roof portion, said roof portion being provided with inclined sides and gable ends, and the

gable ends being composed of open-work material and being hinged to the base of the top portion.

6. A hen's nest and hatching-coop, comprising a box-shaped base portion and a top roof portion, said roof portion being provided with inclined sides and gable ends, and the gable ends being composed of open-work material and being hinged to the base of the top portion, said top portion being detachably connected with the base portion.

In testimony that we claim the foregoing as our invention we have signed our names, in presence of the subscribing witnesses, this 27th day of June, 1906.

HORACE J. MIER.
DAVID BEAMES.
